UNITED STATES PATENT OFFICE.

WALTER BOESSOW, OF BERLIN-LANKWITZ, GERMANY.

HOCKEY GAME.

Application filed November 27, 1926, Serial No. 151,223, and in Germany March 18, 1926.

My invention relates to a table hockey game in which not only the cleverness of the players plays a rôle, but also power can be displayed in a certain measure; it is suited for dwelling rooms, as well as for club rooms, for instance sport clubs, where sportive occupation is now rendered possible also as regards the hockey game.

I am aware of the fact that there exist a plurality of games of somewhat similar character intended to be played in rooms but they are not so designed as to be worthy of being termed sportive games; they are unable to attract actual sportsmen. Matters are different with the present table hockey.

As this hockey is intended for use in rooms it is a matter of course that its dimensions must be limited, the more, as it is intended for use on a table. I do not claim these features as new, nor the provision of so-called goals, but I claim certain important details connected with the table or the play-ground formed by the table plate. There is, first of all, an inelastic bordering frame or rim running along all sides of the table plate and having a height of about 4 inches and being suitably thick. I wish it however, to be understood that said plate need not actually be that of an actual table, but may be any other smooth plate supported on feet or the like. At any rate, there is said bordering frame or rim around it, and it is fastened preferably by fish-plate and bolts or screws or the like. It is suited to the purpose to tilt the said frame or rim a little inwardly.

The plate or table plate is generally oblong, and this being so I provided the above-mentioned so-called goals in the short sides of the rim, that is to say, one goal in the middle of each of the two short sides, each goal being formed by a rectangular recess in the lower rim of the respective side, and the length of each recess corresponding to about twice the diameter of a ball as used in the game. Outside each recess a catch basket or the like is attached to the plate or table.

The frame or rim can be taken to pieces, or can be collapsed, in order to reduce its bulk when having been detached from the plate or table. The frame or rim parts may be either singly, and means may be provided for attaching the individual parts to the respective plate and, may be, also for connecting them with each other; or the parts may

be kept connected with each other continually by hinges or the like. Also feathers and grooves and similar means may be provided.

The improved table hockey game is illustrated diagrammatically and by way of example on the accompanying drawing on which Figure 1 is a vertical cross section through a plate provided with an inwardly inclined rim, Figure 2 is a plan of a plate and its rims, a part of the plate and the rims being broken away; Figure 3 is a vertical section through a portion of a plate and the appertaining rim, this figure being drawn to an enlarged scale and showing a modification; Figure 4 is a similar view showing a section through the middle of one of the short rims where there is the goal, together with the appertaining catch basket; Figure 5 shows two rim portions connected with each other by feather and groove, and Figure 6 is a view of a beating staff as used in connection with the game, or, more precisely, with the balls of the same.

The rim or frame shown in the drawing consists of wood, metal, slate or any other inelastic material, and its cross-sectional area is such that it does not vibrate when a ball is running against it. The rim consists of longitudinal members 1 and transverse members 2, and the several parts constituting the complete rim are connected with each other by intermediate connecting members 3 located in the middle of the long sides, and by corner pieces 4, as shown in Fig. 2. The rim parts are firmly connected with the table plate by screw clamps 5 and spring clamps 6, and each rim part may be provided, if desired, with stiffening brackets 13 (Fig. 3).

Each of the transverse rim parts 2 is provided with a recess 7 forming a goal, and outside the same is provided a wire basket 9 which serves as ball catch and is as high as the rim 2. The wire basket or ball catch 8 is covered with a netting 9 and secured to the rim by screw connections 10 or the like.

The beating staffs 11, Fig. 6, have each a curved end 12 which is covered with a layer 14 of a fabric, rubber or the like in order to dampen the noise arising when a beating staff propels a ball. The balls (not shown) consist of polished steel or the like and may also have a covering of rubber in order to still more dampen the noise.

A game may be played by 4 or 6 or 8 per-

sons. There are drawn in front of each goal two semi-circles, the one having a radius of about 3 inches, the other radius of about $5\frac{1}{2}$ inches; the semi-circles are drawn with chalk, paint or the like. The goal keepers are not allowed to approach the goals nearer than to the inner semi-circle, where as the outer semi-circle serves as beating limit for the other players, viz, the backs and the forwards. It is suited to the purpose to choose distinct and different colors for the goals, for instance red and green. With the simplest way of playing the game, in which case there are four players, there is no further subdivision of the play field. The forwards which are at the same time the backs have the goal corresponding to their color at the left.

If 6 persons are playing the game, the play field is subdivided into 6 portions or sub-fields by a line lying in the axis of the goals, and by two lines lying at right angles thereto, the subdivisions being made in this way that the two inner sub-fields are smaller than the other sub-fields, or corner fields respectively. The red forward has his place lefthand from the green goal keeper, and opposite the red forward and righthand from the green goal keeper has the green back his place, whereas righthand from the red goal keeper the green forward and lefthand from him the red back have their places. The forwards are, thus, at one of the longitudinal sides of the play field and the backs at the other. The backs are, therefore, confined to their corner fields and the common free middle field, whereas the forwards can run from their own play fields also upon the middle field and the opposite back field. If there are 8 players, the play field is subdivided into four portions or sub-fields by a chalk or color line drawn through the goals, and by two lines drawn each righthand from each goal at right angles to said axial line and at about one third of the length of this latter, there being, thus formed right-

hand from each goal a field portion or sub-field of about one sixth of the entire play ground. The green back has his place lefthand from the green goalkeeper; at the side of this latter, in the middle of the respective longitudinal side with the common play field portion, the red half-back has his place, and at the side of this latter and righthand from the red goal the green forward has his place. The succession at the other longitudinal side is this: lefthand from the red goalkeeper the red back; at his side, in the middle, the green half-back, and righthand from the green goalkeeper the red forward.

This having been made clear, the sportive character of the game in connection with the rigid bordering rim and the beating staff becomes obvious from the facts that cleverness, as well as a certain display of power, is necessary to beat the ball away, as well as to keep it off, the rigidness of the bordering rim and the inelasticity thereof being duly considered.

I claim:

1. A table hockey game, comprising, in combination with the plate serving as play ground, an inwardly inclined rigid oblong bordering rim having goals in its shorter sides and being so thick as to be unable to vibrate, and catching means arranged outside said goals and being as high as said bordering rim, substantially as set forth.

2. A table hockey game, comprising, in combination with the plate serving as play ground, an inwardly inclined rigid oblong detachable bordering rim composed of members adapted to be connected with each other and being so thick as to be unable to vibrate, means for securing said rim members to said table, and catching means arranged outside said goals and being as high as said bordering rim, the members located at the short sides of said table having each a goal in the central longitudinal axis of the said table, substantially as set forth.

WALTER BOESSOW.
